To all whom it may concern:

Be it known that I, Joseph W. Figure 1 of the drawing is a front elevational view of a couch embodying my design; and Fig. 2 is an end elevational view thereof.

The distinctive feature of my design resides in long pillow-like or heavy beam-like elements extending along the ends of the body of the structure from front to rear and giving to the couch the aspect of being supported from the floor by the same.

I claim:
The ornamental design for a couch or the like, as shown and described.
